UNITED STATES PATENT OFFICE.

FREDERICK KEEPS AND SERENUS M. COLBURN, OF MINNEAPOLIS, MINNESOTA.

AUTOMOBILE CLOCK-HOLDER.

1,307,053.

Specification of Letters Patent. Patented June 17, 1919.

Application filed November 9, 1917. Serial No. 201,132.

To all whom it may concern:

Be it known that we, FREDERICK KEEPS and SERENUS M. COLBURN, citizens of the United States, residents of Minneapolis, county of 5 Hennepin, State of Minnesota, have invented certain new and useful Improvements in Automobile Clock-Holders, of which the following is a specification.

The object of our invention is to provide 10 a means for mounting a time piece on the dash-board of a vehicle in position where the dial will be plainly visible to the driver and where it will present a neat, ornamental appearance on the car.

15 A further object is to provide a holder or mounting of simple, economical construction which will securely support the time piece and prevent it from shaking or rattling when the car is in motion.

20 The invention consists generally in various constructions and combinations, all as hereinafter described and particularly pointed out in the claims.

In the accompanying drawings forming 25 part of this specification,

Figure 1 is a detail sectional view of a portion of a dash-board with our improved time-piece mounted thereon.

Fig. 2 is a detail view of the case or cover 30 of the time piece,

Fig. 3 is a sectional view on the line 3—3 of Fig. 1,

Fig. 4 is a detail view of the inner support or ring whereon the time piece is seated.

35 In the drawing, 2 represents a suitable support such as a dashboard of a vehicle. 3 is a time piece of suitable size, preferably in watch form, having a winding stem 4 and crown 5. 6 is a band or ring of comparatively thin metal, divided or split transversely at 7, the abutting ends being separated by the tension of the spring material of which the band is preferably made. A recess 8 is formed in one edge of the band and

40 a series of lugs or tongues 9 are pressed inwardly from the band at intervals to form horizontal supports within the circumference of the band. On these supports the time piece is placed with its stem resting in the

45 recess 8. 10 represents a shell or casing in the form of a band or ring, having an inwardly and downwardly turned flanged edge 11 which is adapted to contact with the case of the time piece and hold it securely on the

50 supporting lugs 9. The band or ring 6 through its tendency to expand fits snugly

within this shell or casing though free to slide therein. The other edge of the shell has an outwardly turned flange 12 terminating in a downwardly turned lip 13 which rests upon the dash 2 and this flange is secured to the dash by suitable means, such as screws 14. When these screws are tightened the band 6, resting on the support, will be pressed outwardly, the flange 12 will be put 60 under tension and the shell drawn inwardly toward the dash to press the flange 11 against the case of the time piece and hold it securely on the lugs 9 which are adapted to yield slightly and coöperate with the flange 65 11 for gripping the case of the time-piece between them, and holding it firmly against shaking or rattling. The shell has an opening 15 in its side wall of sufficient size to allow the insertion of the head 5 there- 70 through and the upper portion of this opening has an offset or extension 16 therein, the edge of which is adapted to bear on the stem 4 when the parts are assembled and press it firmly down into the recess 8 in the support- 75 band. We are thereby able to hold the time piece in place while permitting its dial to be easily read from the driver's seat and whenever desired, the winding stem may be manipulated through the head 5 without re- 80 moving the time piece from its supports. This holder may be made in various sizes and in various ways the details of construction may be modified and still be within the 85 scope of our invention. 90

We claim as our invention:

1. A time piece holder comprising a band adapted to rest upon a suitable support and having lugs pressed inwardly therefrom to form supports for a time piece placed thereon, the wall of said band having an opening to receive a winding stem and a shell encircling said band and also having an opening for said stem and provided with an inwardly turned portion for bearing on said time piece, 95 and said shell having means for mounting it on said support, said mounting means when tightened gripping the time piece between said lugs and said inwardly turned portion. 100

2. A time piece holder comprising a band adapted to be seated against a support and having inwardly projecting lugs formed thereon and a recess in its outer edge, a time piece seated on said lugs and having a stem projecting through said recess, a shell en- 105 circling said band and having a flanged edge seated against said support and means pass- 110

ing through said flanged edge for drawing it and said shell toward said support, said shell having an inwardly turned edge between which and said lugs the time piece is clamped 5 with a yielding pressure.

3. A time piece holder comprising a band of spring material divided transversely to form an expandible ring, the walls of said band having time piece supports thereon, a 10 shell into which said band is fitted and held by the spring tension of its walls, said shell having an inwardly turned outer portion between which and said supports the time piece is placed, and means for securing said shell 15 to a support and pressing said band against said support to force said band outwardly into said shell.

4. A time piece holder comprising a band having lugs pressed inwardly therefrom to 20 form supports for the time piece, the wall of said band having an opening therein to receive the winding stem of the time piece and

a shell encircling said band and also having an opening for said stem and provided with an inwardly turned outer edge for bearing 25 on the time piece and pressing it against said lugs, said shell having an outwardly turned inner portion terminating in a downwardly turned edge for bearing on a suitable support and holding the walls of said shell 30 out of contact therewith, said outwardly turned portion forming a spring flange, and screws passing through said flange for securing said shell and clamping the time piece between said lugs and the inwardly turned 35 edge of said shell with a yielding pressure.

In witness whereof, we have hereunto set our hand this 25 day of October, 1917.

FREDERICK KEEES.
SERENUS M. COLBURN.
